WRINGER BRACE FOR LAUNDRY TUBS

Rowland John Curtis, Dover, Ohio, assignor to
The Reeves Manufacturing Company, Dover,
Ohio, a corporation of Ohio

Application June 26, 1934, Serial No. 732,429

5 Claims. (Cl. 68—32)

The invention relates to a device in the form of a stiffening member or brace arranged to be located between two laundry tubs for clamping a clothes wringer thereon and more particularly to a device of this kind especially adapted for use in connection with square sheet metal tubs.

The object of the improvement is to provide a brace or stiffening member adapted to be placed between the upper portions of two adjacent tubs so as to brace or strengthen the side walls of the tubs at the point where the clothes wringer is clamped thereon.

Another object is to provide a brace of this character which also engages over the rims of the two tubs and holds them solidly together.

A still further object is to provide a brace of this character which also acts as a water deflector to prevent water from dripping down between the tubs.

Another object is to provide a brace of the character referred to formed of sheet metal of substantially triangular cross sectional shape and terminating at its upper end in oppositely disposed downturned flanges adapted to fit over the rim beads of two adjacent tubs.

A further object is to provide such a brace having a convex cap to deflect water dripping thereon into the tubs and prevent its dripping down between the tubs onto the bench or stand on which the tubs are mounted.

The above objects, together with others which will be hereinafter pointed out or which may be apparent from the following description, may be attained by constructing the improved wringer brace in the manner illustrated in the accompanying drawing, in which

Figure 1 is a perspective view of two square laundry tubs mounted upon a stand or bench and having one of the improved braces mounted between the tubs and a wringer clamped thereon;

Fig. 2, an enlarged detail perspective view of the improved brace member to which the invention pertains;

Fig. 3, a fragmentary cross sectional view through the brace showing the connection of the same to adjacent portions of two laundry tubs;

Fig. 4, a detached perspective view of a modified form of the brace without the cap shown in Fig. 2; and

Fig. 5, a view similar to Fig. 3 of the modification illustrated in Fig. 4.

Similar numerals refer to similar parts throughout the drawing.

A bench or stand 10 is shown in Fig. 1, the legs 11 of which may be provided with casters as in-

dicated at 12, by means of which the bench may be easily moved upon the floor. Two substantially square sheet metal laundry tubs 13 are shown mounted upon the stand or bench, these tubs having their lower end portions solidly mounted thereon so as not to move relative to the bench.

Laundry units of this character, comprising a pair of square sheet metal tubs mounted upon a stand or bench have recently come into use and have met with great favor owing to the fact that such a laundry unit possesses all of the advantages of the ordinary stationary tubs beside being easily portable.

The only difficulty in the use of such a laundry unit has been found in cases where it is necessary to clamp a hand wringer onto the tubs so as to pass articles from one tub to the other. Owing to the fact that these tubs are formed of sheet metal, the flat side walls thereof do not provide a sufficiently solid surface upon which to clamp such a wringer.

The present invention contemplates the provision of a brace adapted to be wedged between the adjacent side walls of the two tubs and preferably to fit over the rim beads thereof so as to brace and reinforce these portions of the tubs sufficiently to permit the wringer to be tightly clamped thereon. This brace is of substantially triangular cross sectional shape and may be made of heavy sheet metal as illustrated in the drawing and preferably includes the horizontal bottom wall 14 and the inwardly inclined side walls 15 which may terminate in the oppositely disposed downturned flanges 16 adapted to engage over the rim beads 17 of the two tubs in the manner best illustrated in Figs. 3 and 5.

The inclined side walls 15 of the brace fit against the outside of the adjacent side walls 18 of the two tubs, as best shown in Figs. 3 and 5, bracing the same and providing a solid surface on the inside of each tub against which to fasten the clamps 19 of the wringer indicated generally at 20, in the manner best shown in Fig. 1 of the drawing.

It will be seen that as the wringer clamps are tightened against the two adjacent side walls 18 of the tubs, the substantially triangular brace member located between the tubs forms a solid abutment bracing and reinforcing the adjacent side walls of the tub and producing a solid structure to support the wringer.

If desired, a preferably convex cap 21 may be connected to the upper side of the brace as indicated in Figs. 2 and 3 for the purpose of not

only additionally strengthening and reinforcing the same but also providing a water deflector to prevent water from dripping between the tubs onto the bench or stand carrying the same.

5 I claim:

1. A wringer support for a spaced pair of laundry tubs, having a plurality of upwardly diverging, substantially flat walls, said support comprising a brace member having upwardly con-

10 verging sides fitting between the adjacent upper edge portions of the two tubs to reinforce the tubs at this point and oppositely disposed downturned flanges secured to the top of said brace member fitting over the rims of the tubs whereby

15 a clothes wringer may be clamped upon these portions of the tubs without distortion of the walls.

2. A wringer support for a spaced pair of laundry tubs, having a plurality of upwardly diverging, substantially flat walls, said support comprising a sheet metal brace fitting between the adjacent upper edge portions of the two tubs to reinforce the tubs at this point, said brace having a substantially horizontal bottom wall, 15

20 upwardly converging side walls and oppositely disposed downturned flanges at the upper ends of said side walls fitting over the rims of the tubs whereby a clothes wringer may be clamped upon these portions of the tubs without distortion of the walls.

25 3. A wringer support for a spaced pair of laundry tubs having a plurality of upwardly diverging, substantially flat walls, said support comprising a sheet metal brace fitting between the adjacent upper edge portions of the two tubs to reinforce the tubs at this point, and means secured to the top 30

35 of said brace member fitting over the rims of the tubs whereby a clothes wringer may be clamped upon these portions of the tubs without distortion of the walls.

having a substantially horizontal bottom wall, upwardly converging side walls, oppositely disposed downturned flanges at the upper ends of said side walls fitting over the rims of the tubs, and a cap secured upon the top of said brace whereby a clothes wringer may be clamped upon these portions of the tubs without distortion of the walls.

4. A wringer support for a spaced pair of laundry tubs having a plurality of upwardly diverging, substantially flat walls, said support comprising a sheet metal brace fitting between the adjacent upper edge portions of the two tubs to reinforce the tubs at this point, said brace having a substantially horizontal bottom wall, 15

upwardly converging side walls, oppositely disposed downturned flanges at the upper ends of

10 said side walls fitting over the rims of the tubs, and a cap secured upon the top of said brace and

having a central, upwardly extending, convex 20

portion, whereby a clothes wringer may be clamped upon these portions of the tubs without distortion of the walls.

5. A wringer support for a spaced pair of laundry tubs having a plurality of upwardly diverging, substantially flat walls, said support comprising a brace member having upwardly con- 25

verging sides fitting between the adjacent upper edge portions of the two tubs to reinforce the tubs at this point, and means secured to the top 30

of said brace member fitting over the rims of the tubs whereby a clothes wringer may be clamped upon these portions of the tubs without distortion of the walls.

ROWLAND JOHN CURTIS.
